A. D. T. LIBBY & E. J. TOMLINSON.
ELECTROMAGNETIC STRUCTURE.
APPLICATION FILED NOV. 11, 1916.

1,275,572.

Patented Aug. 13, 1918.

UNITED STATES PATENT OFFICE.

ALBION D. T. LIBBY, OF EAST ORANGE, AND EDWARD J. TOMLINSON, OF NEWARK, NEW JERSEY, ASSIGNORS TO SPLITDORF ELECTRICAL COMPANY, OF NEWARK, NEW JERSEY.

ELECTROMAGNETIC STRUCTURE.

1,275,572.

Specification of Letters Patent. Patented Aug. 13, 1918.

Application filed November 11, 1916. Serial No. 130,833.

To all whom it may concern:

Be it known that we, ALBION D. T. LIBBY and EDWARD J. TOMLINSON, citizens of the United States, and residents of East Orange and Newark, respectively, in the county of Essex and State of New Jersey, have invented certain new and useful Improvements in Electromagnet Structures, of which the following is a specification.

10 This invention relates to an electro-magnetic structure having an electro-magnet made up of one or more windings and controlling two armatures, all mounted as a unitary structure on a base particularly designed to receive said structure.

Our complete electro-magnetic structure is especially adapted for use in connection with the operation of a generator used on a variable speed engine such as used in auto-20 vehicles.

One of the objects of our invention is to provide an electro-magnet having a core that is simple and consequently cheap to manufacture and one which will serve several other functions as well as that of carrying the magnetic flux produced by the winding or windings around said core.

Another object of our invention is to provide a base for mounting the electro-magnet proper, on and from which may be derived other parts used in the complete assembled structure thereby reducing the number of operations to produce the entire structure and consequently the cost thereof.

Other and further objects of our invention will be apparent to those familiar with this type of apparatus from an inspection of the specification and drawing attached thereto.

In the drawing Figure 1 is a top plan view 40 of our complete assembled structure with the cover removed.

Fig. 2 is a left hand elevation of Fig. 1.

Fig. 3 is a right hand elevation of Fig. 1.

Fig. 4 is a plan view of the base upon 45 which an electro-magnetic structure is mounted showing in dotted lines the outline of other parts obtained from the base.

Fig. 5 is a perspective view of the blank used in the construction of the core of the 50 electro-magnet.

Fig. 6 is a perspective view of the complete core assembly made up of two of the parts shown in Fig. 5.

Referring now more particularly to the 55 various parts shown in the drawing, 1 is a base, preferably of non-magnetic material, from which the bracket 2 is thrown up to carry the electro-magnet coil structure 44. From the base 1 is also obtained the parts 60 3, 4, 5, and 6 from which are formed the contact members having the same numbers and illustrated in their operative positions in Figs. 1, 2, and 3. When the base 1 is blanked out the contact members 3, 4, and 5 65 and support arm 6 are punched from the base at the same time that the supporting bracket 2 is thrown upward. Support bracket 2 has an ear 7 bent at right angles thereto. The ear 7 has a hole 8 for the purpose of receiving the screw that is used to hold the protecting cover over the base. The protecting cover, (not shown) is adapted to fit around the ledge 9 of base 1. Supporting bracket 2 also has another ear 10 used for 70 the purpose of supporting the resistance coil 11 which is fastened thereto by a screw 12 and nut 13.

In the construction of small electro-magnets it has been the universal practice in the 80 past to use round cores the same being made up on automatic screw machines. One of the chief difficulties of this construction is the difficulty of fastening the heads on to the core so that during the process of 85 winding these heads are very apt to become loosened and forced out of their proper position and it frequently happens that, due to the movement of these heads in the subsequent assembly and operation, the fine wire 90 usually used in coils of this character becomes broken and hence the entire coil assembly must be scrapped. It is also recognized by skilled mechanics that in general screw machine products are much more 95 expensive than punched ones. By our method of constructing the core we avoid the above mentioned objections and at the same time produce a coil structure that is much more rigid and one in which the core can be used 100 for other purposes without adding additional parts. In making the core itself we obtain from the proper kind of material a blank 14 which is subsequently formed into the shape shown by the piece 15 in Fig. 6. 105

Another similar piece 16 is riveted to the piece 15 by rivets 17. Two holes 18 appear in the wings 19 and 20. These holes are

adapted to receive the screws 21 for holding the coil structure onto the support bracket 2. Arms 22 and 23 are formed on the other end of pieces 15 and 16. These arms have screw holes 24 to receive screws 25 which are used for the purpose of attaching the armatures 26 and 27 thereto, through the medium of reed members 28 and 29 which are riveted to their respective armatures by rivets 30.

10 After the core members 15 and 16 are riveted together as above described one end is tapped at 31 for the reception of screw 32 by which the core is fastened to the end supporting arm 6, same being insulated from the base 1 by suitable insulation. The arms 22 and 23 also have tapped holes 33 and 34 to receive the screws 35 and 36 that are used for the purpose of applying tension to the reed members 28 and 29. In order to prevent the screws 35 and 36 from turning a resilient member 37 is clamped between support arm 6 and the ends of the core pieces 15 and 16 by screw 32. The ends of resilient member 37 have knife edges 38 thrown up for the purpose of engaging notches on the screw heads 35 and 36 in order to prevent the screws from turning due to vibrations to which the entire structure is subjected. It will readily be seen that this 25 method of constructing the core of the electro-magnet provides a means of fastening the same to the base by means of screws spaced considerable distant from the center line of the core thereby preventing all tendencies for the electro-magnet to turn about the center. Furthermore the ends of the core are formed to provide a support for the operating armatures and also a support for the means to adjust the armatures to their 30 proper working position. Where round cores are used a special piece to take the place of the arms 22 and 23 of the core pieces 15 and 16 must be provided and a special means of attaching this member to the core 35 must also be provided. Our construction eliminates these extra parts and the attendant difficulties required in their construction and assembly.

It will be noted that the armature 26 carries a contact 39 and the armature 27 carries a contact 40. After the members 3 and 4 are blanked out of the base they are formed into the shape shown more clearly in Fig. 2 and contacts 41 and 42 mounted thereon to coöperate with the contacts 39 and 40 on the armatures 26 and 27. Member 5 after it is punched from the base is bent to the form shown in Fig. 2 for the purpose of acting as a stop for the armature 27. The upper end of the stop member 5 is bent over at 43 so as to prevent the cover when it is put on to the base 1 being shoved down on to the contacts 40 and 42. Contact members 3 and 4 and stop member 5 are suitably insulated from the base 1 for

the purpose of operating in their respective circuits in the proper manner, but inasmuch as the electrical circuits used in connection with our magnetic structure forms no part of our present invention they are not shown or described herein.

It will be readily understood that various changes and alterations may be made in the details of our device but such changes and alterations are believed to come within the scope of the appended claims.

Having thus described our invention what we claim is:—

1. An electro-magnetic structure comprising in combination, a base member, a punched core, windings for said core, and armatures to be actuated by said windings, said core serving as a means whereby the same is supported at both ends by the base member and also as a supporting means for said armatures.

2. An electro-magnetic structure comprising in combination, a base having an up-turned bracket thereon, a punched core, windings for said core, and armatures to be actuated by said windings, said core having one end fastened to the base, said core end also serving as a support for said armatures, said core having its other end co-operating with the up-turned bracket to furnish a support for said core at that end.

3. An electro-magnetic structure comprising in combination, a base member, a core, armature members, and a winding upon said core, said core being made of two punchings fastened together and being shaped to form symmetrical out-turned flanges at both ends thereof, the flanges at one end of said core serving as a means of supporting the same upon the base member and the flanges at the other end serving as a support for said armature members.

4. An electro-magnetic structure comprising in combination, a base member having an up-turned supporting bracket, a punched core having flanges at each end thereof, armature members, and a winding for said core, said up-turned bracket coöperating with the flanges at one end of said core to support said core upon the base member, the flanges at the other end of said core serving as a supporting means for said armature members.

5. An electro-magnetic structure comprising in combination, a base having an integral supporting member thereon, a punched core, and windings for said core, said core having flanges at one end to coöperate with said integral supporting member thereby furnishing a support for said core end upon said base, said core having flanges at the other end and a second support fastened to said base and core between said last mentioned flanges.

6. An electro-magnetic structure comprising

ing in combination, a base member, a punched core having integral flanges at one end thereof, armature members and means to adjust the tension on said armature members, means supported by said core for locking said adjusting means in position, the integral flanges of said core serving as a support for said armature members and also as a support for the adjusting means, and 10 means to support all the above mentioned parts upon said base.

7. An electro-magnetic structure comprising in combination, a base having an up-turned bracket thereon, a core formed of 15 punchings shaped to give symmetrical flanges at each end thereof, armature members, means to adjust the tension on said armature members, resilient means coöperating with the last mentioned means to hold 20 the same in its adjusted position, the flanges at one end of the core being fastened to said upturned bracket to furnish a support for said core, the flanges at the other end of said core serving as a support for said armature 25 members, and means serving as a second support for the core upon said base and also to fasten said resilient means to said core.

8. An electro-magnetic structure comprising in combination, a base member having an 30 up-turned bracket, armature members, means for adjusting the tension on said armatures, a core formed of two punchings fastened together, flanges at one end of said core formed by an oppositely outward bend of said 35 punchings at right angles to the body of said core, flanges at the other end thereof formed by an oppositely outward bend of said punchings at right angles to the body of the core and then a second bend of said 40 punchings at right angles to said first bend, whereby these last mentioned flanges form a partial inclosure, said last named flanges serving as a support for said armatures, said inclosure serving as a protection for said 45 adjusting means, and the first mentioned flanges of said core serving as a supporting means for the same upon said up-turned bracket.

9. An electro-magnetic structure comprising in combination, a non-magnetic base, a 50 punched core, armature members, said core being formed at one end to provide a support for said armature members, and integral flanges at the other end thereof serving 55 as pole pieces for the armature members and also as a means whereby said core is supported upon said base.

10. An electro-magnetic structure comprising in combination, a non-magnetic base 60 having an integral up-turned bracket, a punched core, armatures supported on different punchings of said core at one end thereof, and integral out-turned flanges at the other end of said core, said out-turned 65 flanges serving as pole pieces for said ar-

matures and also coöperating with said up-turned bracket to furnish a support for said core upon said base.

11. An electro-magnetic structure comprising in combination, a non-magnetic base 70 member, a punched core, armature members supported by said core and having contacts thereon, stationary contacts adapted to co-operate with said armature contacts, members stamped from and so mounted upon 75 said base as to serve as supports for said stationary contacts, and a bracket up-turned from said base for supporting said core upon the base member.

12. An electro-magnetic structure comprising in combination, a non-magnetic base, a core formed of punchings, armatures supported by said core punchings and means for adjusting the tension on said armatures, said adjusting means also being supported 80 by said core punchings, and members stamped from the base and arranged thereon at each end of said core thereby serving as a support for said core upon said base.

13. An electro-magnetic structure comprising in combination, a base member, a two piece core and windings therefor, said core pieces being formed and arranged within the windings as to be T-shaped at one end and U-shaped at the other, armatures supported on the U-shaped ends of said core pieces and extending lengthwise the body of said core pieces, said T-shaped ends serving as pole pieces to coöperate with said armatures, and supporting means extending 90 from said T-shaped ends to said base.

14. An electro-magnetic structure comprising in combination, a base member, a two piece core and windings therefor, said core pieces being formed and arranged within 100 the windings as to be T-shaped at one end and U-shaped at the other, armatures supported on the U-shaped ends of said core pieces and extending lengthwise the body of said core pieces, said T-shaped ends serving as pole pieces to coöperate with said armatures, supporting means extending from 110 said T-shaped ends to said base, and an auxiliary support for said core mounted upon said base and attached to said core at 115 the union of said U-shaped ends.

15. An electro-magnetic structure comprising in combination, a base member, a punched core having integral flanges at one end thereof, armature members and means 120 to adjust the tension on said armature members, means supported by said core for locking said adjusting means in position, the integral flanges on said core serving as a support for said armature members and also as 125 a support for the adjusting means, and means including brackets punched from said base and arranged at each end of said core whereby all the above mentioned parts are supported upon said base member.

- 4
16. An electro-magnetic structure comprising in combination, a base having an upturned bracket, a punched core having flanges at one end thereof serving as pole pieces, armatures supported by said core and adapted to coöperate with said pole pieces, a coil for said core, an auxiliary coil, said flanges serving also as a means for supporting said core upon said upturned bracket, and said bracket further serving as a support for said auxiliary coil.
17. An electro-magnetic structure comprising in combination, a base member, a core formed of two punchings out-turned oppositely at each end to give a pair of symmetrical flanges at both ends of said core, a coil wound upon said core, reed members attached to the flanges at one end of said core, armatures secured to said reeds and disposed substantially parallel to each other on either side of said core, said flanges at the other end of said core serving as pole pieces for said armatures, and means whereby all of said parts are mounted upon the base member.
18. An electro-magnetic structure comprising in combination, a base having an upturned bracket, a punched core having flanges at both ends thereof, reed members supported by the flanges at one of said ends, 30 means supported by these last named flanges to adjust the tension on said reed members, the flanges at the other end of said core serving as pole pieces and also coöperating with said upturned bracket to furnish a support 35 for said core, and armatures fastened to said reed members and adapted to coöperate with said pole pieces.
19. An electro-magnetic structure comprising in combination, a base member, a 40 punched core formed to give flanges at both ends thereof, a coil upon said core, said flanges serving as a means of supporting said core upon the base member and also serving as heads for the spool upon which 45 said coil is wound.

In witness whereof we affix our signatures.

ALBION D. T. LIBBY.
EDWARD J. TOMLINSON.
